PULVERIZED-COAL-BURNING LOCOMOTIVE

Application filed March 6, 1925. Serial No. 13,503.

This invention relates to locomotives burning pulverized coal or other finely divided fuel.

A locomotive fire box, because of clearances and other practical limitations, is of comparatively small size.

One of the primary objects of my invention, therefore, is to obtain maximum length of travel for the fuel and flame within the 10 fire box.

Another object is to minimize difficulties encountered with the closing or honeycombing over of the flues by refuse matter.

Still other objects of the invention are to 15 insure and promote proper and rapid combustion within the fire-box; and to obtain high boiler efficiency and evaporation.

Still another object of the invention has 20 to do with the extension of the life of such refractories as may be needed within the box for baffling and combustion purposes. In this connection the duty imposed upon such bricks, particularly where the fuel is burned in powdered form, is very severe.

25 The foregoing, together with such other objects as may hereinafter appear, or are incident to my invention, are realized by a construction which I have illustrated in preferred form in the accompanying drawings,

30 wherein

Fig. 1 is a longitudinal section thru a locomotive fire box embodying my invention.

Fig. 2 is a half section taken on the line 2-2 and a half section taken on the line 35 2a-2a of Fig. 1;

Fig. 3 is a section taken on the line 3-3 of Fig. 1;

Fig. 4 is a section taken on the line 4-4 of Fig. 1; and

40 Fig. 5 is a section similar to Fig. 3 illustrating a modification of the invention.

Referring now to Fig. 1, there is shown the usual form of inside and outside fire-box, respectively comprising the flue sheet 7, the inside back sheet 8, the inside side sheets 9, the inside throat sheet 10 and the crown sheet 11, and the outside throat sheet 12, outside back sheet 13, outside side sheets 14 and cover or roof sheet 15. This box is arranged 45 so as to provide the usual water legs closed at

the bottom by the mud ring 16. The flues 17 lead forwardly from the flue sheet in the usual manner. A door opening 18 is provided in the back head, which door opening, in this instance, is normally closed by the 55 door 19.

Extending downwardly from the box, from the region of the mud ring 16 is a fire pan A consisting of a metallic shell member 20 lined at the sides, rear and bottom with 60 refractory material a. The front wall of the fire pan is in substantial alignment with the inside throat sheet 10 and it is covered by a refractory wall b extending upwardly to the circulation tubes 21.

The circulation tubes 21 connect the front and rear water legs, rising upwardly and rearwardly from the front water leg. These tubes are spaced much more closely than is customary in locomotive practice where, at 70 most, four such tubes are used.

Carried by the tubes 21 and extending from the front water leg rearwardly a portion of the length of the fire box, is a refractory arch or baffle B, the construction of 75 which will be later more fully described.

Extending forwardly and upwardly from the lower portion of the rear water leg is a set of circulation tubes 22, the upper ends of which are expanded into the crown sheet 11 80 at about midway of its length. Both sets of tubes 21 and 22 are bent so as to provide more readily for expansion and contraction. The tubes 22 intersect with the tubes 21, passing therebetween, at a point about midway of 85 the length of the fire box and above the middle point in its height. The tubes 22 carry an arch C of refractory bricks to be herein-after described.

It will be observed on inspection of Figs. 90 1, 2 and 3 that the tubes 21 have longitudinal fins 23 secured on opposite sides thereof and extending part of the distance from the front water leg to the rear water leg. These fins are preferably welded on and are of such 95 width as will enable them to conduct heat to the tubes without burning off. The side tubes 21 have only one such fin.

The arch B is composed of center brick 24 and wing brick 25. The center bricks are 100

somewhat T shaped and, by virtue of the close spacing of the tubes 21, are of relatively small dimension, this dimension being further decreased in the web portion of the bricks 5 by virtue of the presence of the fins. Hence, it will be observed that in so far as the center bricks are concerned there is, comparatively speaking, but a relatively small aggregate surface of refractory material presented to 10 the flames. Such bricks are protected by the tubes and fins not only because the latter directly shield the bricks, but also because they absorb heat therefrom. The cooling effect of the tubes and fins on the tongues or 15 vertical legs of the bricks is such that they will not wear out rapidly. The wing bricks are protected by the cooling effect of the side sheets and the side tubes. Since these bricks do not wear out as rapidly as the center bricks, they do not need protection to the same extent.

The tubes 22 are similarly provided with fins 23, such fins terminating at about the point of intersection of the two sets of tubes. 25 The rear arch C extends from a point approximate the rear end of the baffle or arch B, a portion of the distance toward the back water leg. This arch consists of center brick 24, such as above described, the wing brick 20 being omitted. The center bricks are held against sliding longitudinally of the tubes 22 by virtue of spacer bricks 26 which are socketed so as to rest on top of the tubes 22, as indicated in Figs. 1 and 2. These spacer 30 bricks engage and support the lowermost center brick of the arch C as indicated in Fig. 2.

For the reasons already pointed out it will 40 be apparent that all of the bricks of the rear arch are protected from the action of the flames and present but a small total area to the flames.

By virtue of the construction of the rear arch, a passageway 27 exists at each side 45 thereof as well as a plurality of passages between the tubes and the lowermost end of the arch C and the water leg. The arches B and C considered together form an inverted V-shaped arch, the forward leg of which 50 abuts against the throat sheet 10 and the rear leg of which terminates short of the sheet 8.

The pulverized coal is supplied from the tender and led to one or more burners D by the pipe or pipes 28, air being preferably used 55 as the carrying medium. Additional air is drawn into the burner or burners and the burners discharge thru the rear wall 29 of the fire box. Immediately above the point of fuel introduction, I provide an arch 30. The 60 side walls of the fire pan are provided with two or more rows of auxiliary air inlets 31, air being supplied to such inlets by virtue of the circumferential duct 32 which may be formed in any desired manner and which 65 is provided with a damper controlled inlet,

not shown, whereby control of the air supply to the auxiliary inlets may be controlled.

Assuming that the fire box is hot enough to institute ignition and carry on combustion, the operation is as follows:

The entering fuel stream is immediately subjected to radiant heat from the incandescent refractories and becomes ignited. The forward wall, in combination with the draft guides turns the fuel and flame stream 70 upwardly toward the arch B by which the fuel and flame stream is guided toward the rear, part of the flame passing upwardly thru the passages 27 at the sides of the arch C and part passing over the rear end of the arch C. 75 The flame then bends and travels forwardly toward the flues. As the fuel enters and as the fuel and flames traverse the fire pan, the fuel particles and the burning gases are continuously brought into contact with fresh air and 80 similarly in its reverse bend, the fuel and flame stream draws upon the air induced thru the inlets 31. The effect of the arches, the tubes, and the various passages is to promote 85 effective mixture.

The forward wall b is subjected to scouring action and is therefore made quite substantial. The arches B and C are protected in the manner already described from that portion of the flame therebeneath. The upper 90 surfaces of the arches radiate heat to the flame thereabove, but since combustion has been already well carried forward and since a large portion of the refuse particles, particularly the heavier ones, have already been tangentially discharged from the fuel and flame stream there is no scouring action of any consequence on the upper faces of the arches.

The fire pan and the arches cooperate to radiate heat to a central locus, insuring proper combustion and overcoming the chilling effect of the side sheets of the fire box. 105

The tubes 21 and 22 are in the nature of screens from which the fuel and flame stream must pass and they, of course, absorb a large 110 quantity of heat, in consequence of which whatever refuse particles are carried over the arches forwardly, are cooled to the extent such as minimizes honeycombing or bridging effects over the flues.

The refuse which is formed and deposited in the fire pan runs to the discharge hopper E.

It will be seen from the foregoing that I have provided an effective arrangement for subjecting the fuel to radiant heat and for supplying the fuel with air as combustion proceeds and for protecting the baffles as well as the flues, at the same time securing the maximum length of flame travel, and a perfect mixture of fuel and air, whereby combustion is completed within the fire box. 120

In the arrangement of Fig. 5 the fins are omitted, reliance being placed upon the tubes alone for the protection of the refractories. In all constructions it will be seen that even if 125 130

the legs of the center brick wear off substantially nevertheless the bricks will be substantially socketed between the tubes so that there is very little liability of any of such brick being dislodged.

Since locomotives ordinarily have comparatively short runs, as compared to stationary practice, there is ample opportunity provided for cleaning out any deposits of refuse at points other than in the hopper.

10 The fire pan is carried from the mud ring as shown, whereby the same may be readily applied to existing locomotives. The method of support is a convenient way for providing an air supply duct.

15 The zone defined by the pan, front wall and the arches may be termed a main combustion space in which ignition, partial combustion and gasification take place. Here there is room for expansion. The remaining portions of combustion space are smaller in cross section as the gases contract somewhat because of the absorption of heat. The former region is, therefore, largely bounded by refractories for combustion purposes and is preferably larger.

I claim:

1. In a pulverized fuel burning locomotive, a fire-box having rearwardly and upwardly extending circulation tubes and upwardly and forwardly extending circulation tubes crossing one another, burner means at the rear of the box for admitting fuel beneath the tubes in a forward direction, an arch carried by the first tubes and extending for the width of the box part way from the front to the rear leg, and an arch carried by the second tubes and extending from the first arch part way to the rear leg.

20 2. In a pulverized fuel burning locomotive, a fire-box having rearwardly and upwardly extending circulation tubes and upwardly and forwardly extending circulation tubes crossing one another, burner means at the rear of the box for admitting fuel beneath the tubes in a forward direction, an arch carried by the first tubes and extending for the width of the box part way from the front to the rear leg, and an arch carried by the second tubes and extending from the first arch part way to the rear leg and terminating substantially short of the side sheets.

25 3. In a pulverized fuel burning locomotive, a fire-box having rearwardly and upwardly extending circulation tubes and upwardly and forwardly extending circulation tubes crossing one another, burner means at the rear of the box for admitting fuel beneath the tubes in a forward direction, an arch carried by the first tubes and extending for the width of the box part way from the front to the rear leg, and an arch carried by the second tubes and extending from the first arch part way to the rear leg and terminating substantially short of the side sheets, to-

gether with a refractory fire pan below the arches.

4. In a pulverized fuel burning locomotive, a fire-box having rearwardly and upwardly extending circulation tubes and upwardly and forwardly extending circulation tubes crossing one another, burner means at the rear of the box for admitting fuel beneath the tubes in a forward direction, an arch carried by the first tubes and extending for the width of the box part way from the front to the rear leg, and an arch carried by the second tubes and extending from the first arch part way to the rear leg and terminating substantially short of the side sheets, together with a refractory fire pan below the arches and means above the bottom of the pan and beneath the arches for admitting air for combustion.

5. In a pulverized fuel burning locomotive, a fire-box having rearwardly and upwardly extending circulation tubes and upwardly and forwardly extending circulation tubes crossing one another, means for admitting fuel therebeneath, an arch carried by the first tubes and extending for the width of the box part way from the front to the rear leg, an arch carried by the second tubes and extending from the first arch part way to the rear leg and burner means at the rear of the box for admitting fuel forwardly beneath the arches together with a third arch overlying the burner means and adapted to prevent short circuiting of the fuel and flame.

6. In a pulverized fuel burning locomotive, a fire-box having rearwardly and upwardly extending circulation tubes and upwardly and forwardly extending circulation tubes crossing one another, burner means at the rear of the box for admitting fuel beneath the tubes in a forward direction, an arch carried by the first tubes and extending for the width of the box part way from the front to the rear leg, and an arch carried by the second tubes and extending from the first arch part way to the rear leg and terminating substantially short of the side sheets, together with a third arch overlying the burner means and adapted to prevent short circuiting of the fuel and flame.

7. In a pulverized fuel burning locomotive, a fire box, burner means for delivering fuel into said box in a forward direction adjacent the bottom thereof, an outlet in an upper forward portion of the box and an inverted V-shaped arch below and rearward of said outlet, the rear leg of which terminates short of the rear wall of the box whereby the fuel and flame stream is caused to travel forwardly from the fuel delivering means, upwardly, rearwardly below said arch and upwardly and forwardly over said arch to said outlet.

8. In a pulverized fuel burning locomotive, a fire box, burner means for delivering

fuel into said box in a forward direction adjacent the bottom thereof, a set of water tubes in said box extending upwardly and forwardly from the rear wall thereof, a second set of tubes in said box extending rearwardly and upwardly from the front wall thereof and separate baffle means supported on the lower portion of said sets of tubes and meeting at their upper edges, the baffle associated with the upwardly and forwardly extending tubes having an opening therethrough adjacent the rear of the fire box, whereby the fuel and flame stream is caused to contact serially with the lower portion of said second mentioned set of tubes, said first mentioned set of tubes and the upper portion of said second mentioned set.

9. In a pulverized fuel burning locomotive, a fire box, burner means for delivering fuel into said box in a forward direction adjacent the bottom thereof, a set of water tubes in said box extending upwardly and forwardly from the rear wall thereof, a second set of tubes in said box extending rearwardly and upwardly from the front wall thereof, an outlet above and forward of said second mentioned set of tubes and separate baffle means supported on the lower portions of said sets and meeting at their upper edges, the baffle associated with the upwardly and forwardly extending tubes having an opening therethrough adjacent the rear of the fire box, whereby the fuel and flame stream is caused to contact serially with the lower portion of said second mentioned set, the lower portion of said first mentioned set, the upper portion of said second mentioned set and the upper portion of said first mentioned set, and to pass to said outlet.

40. In testimony whereof, I have hereunto signed my name.

VIRGINIUS Z. CARACRISTI.
